UNITED STATES PATENT OFFICE

132,118

DESIGN FOR A SET OF NUMERALS

Lester O. Thompson, Oklahoma City, Okla.

Application May 26, 1941, Serial No. 101,139

Term of patent 14 years

To all whom it may concern:

Be it known that I, Lester O. Thompson, a citizen of the United States, residing at Oklahoma City, in the county of Oklahoma and State of Oklahoma, have invented a new, original, and ornamental Design for a Set of Numerals, of which the following is a specification, reference being had to the accompanying drawing, forming part thereof, and in which:

Fig. 1 is a face view of a set of numerals showing my new design; and

Fig. 2 is a cross sectional view on line 2—2 of the zero character of the set of numerals.

My design for a set of numerals is characterized by a plurality of substantially flat rectangular plates with top bevelled edges, each numeral being cut-out through a plate, as illustrated.

I claim:

The ornamental design for a set of numerals, substantially as shown and described.

LESTER O. THOMPSON.
